CLAIM

The ornamental design for a accessory drawer for use
primarily in a mailroom, as shown.

DESCRIPTION

FIG. 1 is a perspective view of a accessory drawer for
use primarily in a mailroom, showing our new design;
FIG. 2 is a top plan view thereof;
FIG. 3 is a front elevational view thereof;
FIG. 4 is a right side elevational view thereof;
FIG. 5 is a left side elevational view thereof;
FIG. 6 is a rear elevational view thereof; and
FIG. 7 is a bottom plan view thereof.

FIG. 1

FIG. 2

FIG. 3

FIG. 4
